UNITED STATES PATENT OFFICE.

JAMES W. WALLS, OF PUEBLO, COLORADO.

SWITCH-STAND.

1,245,167.

Specification of Letters Patent.

Patented Nov. 6, 1917.

Application filed March 6, 1914. Serial No. 822,827.

To all whom it may concern:

Be it known that I, JAMES W. WALLS, a citizen of the United States, residing at Pueblo, in the county of Pueblo and State of Colorado, have invented certain new and useful Improvements in Switch-Stands, of which the following is a specification, reference being had therein to the accompanying drawing.

10 This invention relates to a continuous combination interlocking slip switch; the object being to provide a switch which is so constructed that the switch points are eliminated, thereby overcoming the difficulties 15 now existing with switches of that character in use.

A further object of the invention is to provide a switch in which stub switches or swing rails are enlarged for connecting the 20 gap of the rails of the main and side rails together; the ends of the main and side rails being connected together by plates on which the rails are firmly bolted in order to allow the plates to contract and expand 25 with the rails in such a manner that all danger of the flexible and swing rails binding in their movements, is prevented.

Another object of the invention is to provide novel means for operating the flexible 30 and swing rails together with means for locking the same in adjusted position; said operating and locking means being operated by a combination interlocking switch stand through the medium of which, the rails can 35 be quickly swung into their adjusted positions and locked.

Another and further object of the invention, is to provide a construction which is exceedingly simple, the flexible and swing 40 rails being so mounted upon the base or connecting plates of the main and side rails, that a free movement is obtained.

Other and further objects and advantages of the invention will be hereinafter set forth 45 and the novel features thereof defined by the appended claims.

In the drawings—

Figure 1, indicates a top plan view showing the application of my invention;

50 Fig. 2, is an enlarged top view of one of the spring rails showing the manner of mounting the same;

Fig. 3, is a top plan view of the swing rails showing the manner of mounting the same;

55

Fig. 4, is a transverse section through Fig. 3;

Fig. 5, is a vertical section through my improved construction of combination interlocking switch stand;

60

Fig. 6, is an enlarged top plan view of the head plate of the stand;

Fig. 7, is an enlarged elevation of the head;

Fig. 8, is an enlarged section taken on the line *a—a* of Fig. 7;

Fig. 9, is a detail enlarged vertical section showing the locking mechanism for the lever;

Fig. 10, is an enlarged elevation of the spacing block, showing the rails in section.

Like numerals of reference refer to like parts in the several figures of the drawings.

In the drawings, 1 and 2 indicate the rails of the main track and 3 and 4, the rails of the switch track; the main rail 2 and the switch rail 3 being formed with a gap at the junction thereof, the ends of which are connected together by a connecting or base plate 5 spiked to the ties, upon which the respective ends of the main switch rails are securely bolted and the converging ends of these rails are connected by spacing blocks 6 and 7 provided with bolt openings 8, for the purpose hereinafter fully described.

85

By mounting the ends of the main rails and switch rails rigidly upon a continuous base plate, the plate will expand and contract with the expansion of the rails in order to prevent the swing rail, which will be later described, from becoming wedged between the rails in its swinging movement.

90

The base plate 5 is provided with a central depression 9 in which is mounted, a central depression 10 of a rail plate 11 upon which is securely fastened a swing rail 12 by angled plates 13, said angled plates being provided with housings 14 at their ends for the purpose later described.

95

The angled plates 13 and the rail plate 100 11 are preferably secured in position upon the base plate 5 by a strap or bar 15 extending through apertures substantially in the same manner as disclosed in my patent

numbered 909,351, in order to form an exceedingly strong and durable pivot for the swing rail.

The main rails 1 and 2 are provided with 5 gaps at the intersection of the switch rails 3 and 4 and the ends thereof are mounted upon tapering base plates 16 and 17 which are spiked to the ties in a similar manner to the base plate 5 and as the ends of the 10 respective rails are securely anchored upon these plates, the plates expand and contract with the rails. The intersecting portions of the switch rails and main rails are connected together by spacing blocks 18 and 15 18'; each being provided with a suitable bolt opening.

Arranged between the gaps formed in the main rails, are flexible stub rails 19 and 20 securely bolted to the ends of the 20 main rail at one end, by fish plates which engage angled plates 21 carried by the flexible rails which are also provided with bolt housings 22 at one end to receive the locking bolts, as will be hereinafter fully described.

In constructing a switch as above set forth, it will be seen that all switch points have been eliminated and swing rails substituted therefor which are so mounted upon 30 base plates which connect the ends of the main rails and switch rails at the gaps formed therein, that the flexible stub rails and swing rails are free to move upon the base plates in order to form a continuous rail switch, thereby eliminating the shock and jar caused by a train passing over a switch as now constructed and by means of this construction, the danger of a train becoming derailed, is greatly reduced.

40 In connection with a continuous rail switch as hereinbefore described, I employ a combination interlocking switch stand 22^a by means of which the swing rail and flexible rails are operated simultaneously in connection with locking bolts 23, 24, 25 and 26, which are mounted in the spacing blocks and are adapted to extend in the housings carried by the swing rail and flexible rail so as to lock the movable rails in their 45 adjusted positions, whereby the switch is firmly locked when shifted in either of its positions.

The switch stand 22^a comprises a base 27 having a skeleton portion 28 extending upwardly therefrom, terminating in a depending tubular portion 29 in which is mounted a tube 30 having its lower end mounted in a bearing 31 formed on the base plate 27.

The upper portion of the skeleton stand, 60 is provided with a top plate 32 having notches 33 and 34 to receive the operating lever, which will be hereinafter fully described.

Arranged upon the top plate is a head

member 35 mounted thereon in such a manner that the same is free to turn and is connected to the tube 30 by a key as shown at 36. The head 35 is provided with a hollow enlargement 37 in which is mounted a switch lever 38 upon a pivot 39 which is 70 provided with a pointed lug 40 extending through a slot 41 formed in the tube 30 into a slot 42 formed in a sliding plunger 43 mounted within the tube 30.

The lower end of the plunger 43 is provided with a transversely arranged cotter pin 44 which extends out through a slot 45 formed in the tube 30 for fastening a collar 46 to the plunger, said collar being slidably mounted upon the tube 30 and is 80 preferably provided with an annular groove, into which extend pins 47 carried by a yoke 48 formed on one end of a bell crank lever 49 which is pivotally mounted upon a suitable shaft carried by supports arranged 85 upon the base of the stand so that when the plunger is reciprocated by raising or lowering the lever 38, the bell crank will be swung upon its pivot.

Keyed to the tube 30 below the collar 46 90 is a sleeve portion 50 of a crank arm 51 having a bifurcated portion 52 which is oscillated by the movement of the switch lever when swung horizontally from one of the notches 33 or 34 as the case may be.

95 It will be seen that when the lever is raised so as to move the same out of one of these notches, the head is free to rotate upon the plate so as to operate the crank. In the upward movement of the lever, the plunger 100 rod is operated so as to swing the bell crank, and the connection of these cranks to the operating bars of the switch lock bolts, will be hereinafter fully described.

In order to provide means for locking the 105 switch lever in either of its adjusted positions so as to prevent the same from being raised out of its notch, I provide the lug 40 of the lever 38 with an opening 53 into which is adapted to extend a spring-actuated bolt 54 mounted in the head and operated by a pivoted lever 55 which is engaged by the ward of a key not shown, capable of being extended through a keyhole 56 formed in the casing in alignment with which, is 110 arranged a key post 57.

115 It will be seen that when the ward of the key is turned into engagement with the lever 55, the bolt will be moved out of the opening of the lug of the lever in order to allow 120 the same to be raised into substantially horizontal position so that the same can be oscillated and when the lever is placed in the other notch and dropped into its normal position, the bolt by the action of the spring 125 enters the opening of the lug of the lever and locks the same in that position, whereby an automatic switch lock is obtained for

locking the lever in either of its adjusted positions.

Mounted within the bifurcated end 52 of the crank arm 51 is an operating rod 58 which extends under the plates 16 and 17 and is connected to the respective free ends of the stub rails 19 and 20 by bolts 59 and 60 passing through slots formed in the plates and by means of which the stub rails 10 are moved into either of their positions. The free end of the operating rod 58 is connected to one of the arms of a bell crank 61 mounted upon a suitable support arranged upon the tie as clearly shown, the other arm 15 being connected to a swing rail rod 62 which is connected to similar bell cranks 63 and 64 carried by brackets arranged alongside of the main track as clearly shown, the other arms of these bell cranks being connected to the free ends of the swing rail 9 by rods 65 and 66 through the medium of bolts 67 and 68 which pass through openings formed in the base plate 5 and are connected to the rail plate carrying the swing 20 rail as clearly shown. The bell cranks 63 and 64 are so mounted that when the swing rail rod 62 is reciprocated they are moved in opposite directions so that one pulls on one end of the rail, while the other shoves 25 on the other end of the rail so as to swing it into either of its adjusted positions.

Pivotedly connected to the free arm of the bell crank 49 is a bolt-operating rod 70 which is connected to one of the arms of a crank 71, to which is connected, a rod 72 having connection with a detector bar 73 mounted adjacent the switch rail 4 and constructed substantially as disclosed in my Patent #987,027 dated March 14, 1911.

Connected to the rod 72 is the arm of a crank 74 mounted on one of the adjacent ties to which is connected a rod 72' which extends under the switch and main rails and has a connection with cranks 75, 76 and 77 to 45 which are connected the bolts 24, 25 and 26 working in the respective spacing blocks and adapted to be forced into the housings carried by the angled plates of the swing and flexible rails in order to lock the swing and 50 stub rails in their adjusted positions.

It will be noticed that the lock bolt 24 cooperates with one end of the swing rail and that the bolts 25 and 26 coöperate with the free ends of the flexible rails and while I 55 have shown housings formed on the angled plates to receive the bolts which are slidably mounted within the spacing blocks, it is of course understood that the housings can be dispensed with as the bolt projecting 60 outwardly beyond the spacing block will prevent the rails from moving.

Connected to the free end of the rod 72' is a crank 81 to which is connected a detector bar-operating rod 82 connected to a

detector bar 83 mounted alongside one of the main rails constructed substantially in the same manner as disclosed in my patent above referred to, these detector bars operating and accomplishing the same result as fully disclosed in my patent. 70

A longitudinally arranged rod 84 is also connected to the crank 81 having a crank 85 mounted on a bracket connected to its free end which is connected to a transversely arranged rod 86 extending under the main 75 rails having a connection with a crank 87 at its other end to which is connected the locking bolt 23 working in the opening formed in the spacing block 6 and adapted to coöperate with the housings formed on the ends of the angled plates of the swing rail for locking the same in its adjusted position and it will be seen that by the above construction of connecting the locking bolts, they will be operated in unison in order to 85 release and lock the swing rail and flexible rails in their adjusted positions by the movement of the switch lever, and by the construction as disclosed when the switch lever is in raised position it is free to turn horizontally so as to rotate the tube which operates the crank and operating bar so as to swing the swing rail and stub rails and when in this position, by lowering the lever, the movement of the rails will be locked. 95

It will be seen that the construction of switch stand as herein shown, provides means for unlocking the swing rails by the upward movement of the lever and by the downward movement of the lever they are 100 locked.

I claim:

1. A switch stand having a movably mounted head carrying a pivotally mounted switch lever provided with an opening, 105 mechanism operated by the switch lever in both of its movements to release and operate movable switch rails, and a spring actuated bolt arranged to enter the opening of said lever for locking said lever in lowered position.

2. The combination with a switch stand, of a pivoted lever, cranks operated by the movement of said lever, said lever being provided with an opening, and a spring 115 actuated bolt adapted to enter said opening when said lever is in lowered position.

3. The combination with a switch having movable stub rails, of means for locking said stub rails, a switch stand having a lever 120 for releasing said locking means by the vertical movement thereof, means for swinging said rails by the horizontal movement of said lever, and a spring-actuated key-controlled bolt adapted to enter an opening in 125 said lever for locking said lever in lowered position.

4. In a switch stand, the combination

with movable rails, of means for locking said rails, an oscillating tubular member mounted in said stand, a connection between said member and movable rails, a 5 plunger mounted in said tubular member, a connection between said plunger and locking means, a lever having a connection with said plunger and the tubular member for operating the same, said lever being provided with an opening, and a key-operated 10 spring-actuated bolt arranged to enter the opening of said lever for locking said lever in lowered position.

5. The combination with movable switch 15 rails and means for locking said rails, of a switch stand provided with a plate having notches, of a head movably mounted upon said plate, a tube extending through said head, a plunger mounted within said tube, 20 cranks having connections with said tube and plunger, a lever mounted in said head having a sliding connection with said plunger and tube, and capable of moving in a vertical direction into and out of said 25 notches for releasing said locking means before the movement of said rails, said lever being provided with an opening, and a spring actuated bolt adapted to enter the opening of said lever for locking said lever in an adjusted position.

6. The combination with movable switch 30 rails and means for locking said rails, of a switch stand provided with a plate having notches, of a head movably mounted upon said plate, a tube extending through said head, a plunger mounted within said tube, cranks having connection with said tube and plunger, a lever mounted in said head having a connection with said plunger and 35 tube, capable of moving in a vertical direction into and out of said notches for releasing said locking means before the move- 40

ment of said rails, said lever being provided with an opening, and a spring actuated bolt adapted to enter said opening when said lever is in lowered position for locking said lever.

7. The combination with movable switch 45 rails and means for locking said rails, of a switch stand provided with a plate having notches, a head movably mounted upon said plate, a tube extending through said head, a plunger mounted within said tube, cranks having connections with said tube and plunger, a lever mounted in said head provided 50 with a lug having a sliding connection with said plunger and tube, and capable of moving in a vertical direction into and out of said notches for releasing said locking means before the movement of said rails, 55 the lug of said lever being provided with an opening, and a spring-actuated key-operated bolt adapted to enter the opening in said lug for locking said lever in its adjusted position.

8. A switch stand, having a plate provided with notches, a head mounted upon said switch stand, a lever pivotally mounted in said head, coöperating with said notches, a crank operated by the vertical movement of said lever into and out of said notches, a second crank operated by the horizontal movement of said head, said lever being provided with an opening, and a spring actuated bolt arranged to enter the opening of said lever when in a lowered position.

In testimony whereof I affix my signature in presence of two witnesses.

JAMES W. WALLS.
